UNITED STATES PATENT OFFICE.

ARTHUR C. HOPKINS, OF NILES, MICHIGAN, ASSIGNOR TO NATIONAL-STANDARD COMPANY, OF NILES, MICHIGAN.

LIFTING JACK.

Application filed April 15, 1927. Serial No. 184,008.

The main objects of this invention are: First, to provide an improved lifting jack which may be operated with long or short stroke as desired in raising, and is very

powerful.

Second, to provide an improved lifting jack having friction clutch actuating means in which the clutch is easily released and at the same time is not likely to slip.

Third, to provide an improved lifting jack having these advantages which may be rapidly lowered, at the same time the lowering is under the control of the operator.

Objects relating to details and economies of construction and operation of my invention will appear from the detailed description to follow.

The invention is defined and pointed out in the claims.

A structure which is a preferred embodiment of my invention is illustrated in the accompanying drawing, forming a part of this specification, in which:

Fig. 1 is a perspective view of a lifting jack embodying the features of my invention.

Fig. 1^a is a detail perspective view of the outer portion of the actuating lever.

Fig. 2 is a detail view partially in section on line 2—2 of Figs. 3 and 4, showing structural details.

Fig. 3 is a detail section on line 3—3 of Fig. 2.

Fig. 4 is a detail section on line 4—4 of Fig. 2.

In the drawing similar reference characters refer to similar parts throughout the several views.

Referring to the drawings, the structure illustrated comprises a frame consisting of side members 1, 1 connected in spaced relation by suitable cross members. At its rear end, the frame is provided with an axle 2 for the supporting wheels 3. At the front end of the frame are laterally projecting brackets 4 on which the caster wheels 5 are mounted.

The lifting lever 6 is pivotally mounted on the cross rod 7 extending between the side members.

The head 8 is mounted on the pivot 9 on the outer end of the lifting lever. A link 10 is connected to the head member by the pivot 11 and to the frame by the pivot 12, the link being disposed in parallel relation

to the lifting lever so that as the lifting lever is swung on its pivot, the head is kept in an upright position.

A pair of racks 13 are connected to the lifting lever at 14 in spaced relation to the lever pivot 7. These racks are supported by rollers 15 on the frame cross member 16 so that the racks coat with the elongated pinion 17 having journals 18 in its ends sup-

ported on the frame and bearings formed on the brackets 4. On this pinion is a clutch drum 19 and also a holding ratchet 20. For convenience in manufacture, the drum and ratchet are broached to receive the elongated pinion.

I provide a clutch member designated generally by the numeral 21 and having an annular clutch shoe 22 split at 23, the shoe having a lining or facing designated by the numeral 24. The actuating lever 25 is pivoted at 26 on this clutch member and provided with a thrust member 27 engaging the clutch shoe 22 adjacent the split therein. This thrust member is arranged close to the pivot 26 so that by pressing down upon the lever, a very powerful leverage is secured to close the clutch.

A spring 28 is seated in a holder 29 on the clutch member to engage the actuating lever 25 at the rear of its pivot 26, as shown in Fig. 3, the spring acting to normally engage the clutch or to urge its shoe to engaging position.

An upward lift, however, on the lever swings the thrust member away from the shoe, thereby releasing the clutching pressure.

To hold the clutch against rotation and thereby prevent this releasing operation, I provide the clutch member with a segmental rack 30 with which a reversing pawl 31 contacts, this reversing pawl being normally held in inoperative position, as shown in Fig. 3. The holding pawl 32 coacts with the holding ratchet 20, being held normally in engagement therewith by the spring 33, this spring acting also to hold the pawl 31 out of engagement.

In the lifting operation, the lever 25 is oscillated to release the clutch and allow it to swing around the drum for a new grip, the clutch being released merely by an upward lift on the lever and engaged by a downward thrust thereon. Continued downward thrust rotates the drum which is held

against backward rotation by the holding pawl coacting with the lever. When it is desired to lower the lifting member, the reversing member 34, which is in the form of an annular rack mounted on the shoulder 35 of the ratchet, is actuated to disengage the holding pawl and engage the reversing pawl.

This reversing member 34 is provided with 10 arms 36 and 37, the arm 36 carrying a rod 38 which is pivoted at 39 to the arm, the rod being slidably engaged with the lug 40 on the pawl 31. A coiled spring 41 is arranged between the lug and the shoulder 42 15 on the rod so that as the reversing member is rotated, the thrust of the spring acts to yieldingly urge the pawl 31 into engagement with the rack 30, at the same time the holding pawl 32 is released. This pawl is connected to the arm 37 by means of the rod 43 which is pivoted to the arm 37 at 44, the rod being slideable through a lug 45 on the pawl, a spring 46 being arranged between the lug 45 and the thrust collar 47 so that 20 as the member 34 is rotated, the engagement of the pawls is reversed.

When the pawl 31 is engaged, the rotation of the clutch member is prevented, thereby allowing a releasing of the clutch by 30 lifting upwardly on the lever 25, and if desired, the amount of slipping friction necessary can be maintained to allow the slow return of the lifting lever.

The reversing member is actuated by a 35 dog 48 which is pivoted at 49 on the link 50. This dog has a rearwardly extending tail 51 to which the control rod 52 is connected. A spring 53 is connected to the dog at 54 and to the clutch member at 55, so that by pulling on the control rod, the first action is to 40 swing the dog on its pivot 49, bringing the lug 56 into engagement with the rack of the reversing member 34; continued pull on the rod rotating the rack, and thereby engaging the reversing pawl and releasing the holding pawl.

The control rod is provided with a hand piece 57 adjacent the hand piece 58 of the lever so that the hand pieces may be simultaneously grasped.

My improved lifting jack has a large amount of power; the stroke may be varied to suit the operator or conditions under which it is used; the jack may be easily reversed and quickly lowered, the lowering being under the control of the operator.

I have illustrated and described my improvements in an embodiment which I have found very practical. I have not attempted to illustrate or describe certain modifications or adaptations which I contemplate as I believe this disclosure will enable those skilled in the art to embody or adapt my improvements as may be desired.

Having thus described my invention, what

I claim as new and desire to secure by Letters Patent, is:

1. In a lifting jack, the combination of a frame, a lifting member, a drum operatively connected to said lifting member, a clutch member provided with a rack and with a clutch shoe coacting with said drum, an actuating lever pivoted on said clutch member to coact with said clutch shoe, a spring acting to normally urge the clutch shoe to engaging position, a holding ratchet connected to said drum, a holding pawl coacting with said holding ratchet, a reversing pawl coacting with said rack on said clutch member, a rotatably mounted reversing member 70 provided with a rack and with radially disposed arms, rods pivoted to said arms on said reversing member, said pawls being provided with lugs with which said rods are slidably engaged, springs arranged on said 75 rods and acting to release the holding pawl and engage the reversing pawl on the actuation of said reversing member, a reversing member actuating dog, a supporting link for said dog, a spring acting to hold said dog normally in disengaged position, and a control rod connected to said dog whereby a pull will first engage the dog with the reversing member and a continued pull will actuate the same. 95

2. In a lifting jack, the combination of a frame, a lifting member, a drum operatively connected to said lifting member, a clutch member provided with a rack and with a clutch shoe coacting with said drum, an actuating lever pivoted on said clutch member to coact with said clutch shoe, a spring acting to normally urge the clutch shoe to engaging position, a holding ratchet connected to said drum, a holding pawl 100 coacting with said holding ratchet, a reversing pawl coacting with said rack on said clutch member, a rotatably mounted reversing member provided with radially disposed arms, rods pivoted to said arms on 105 said reversing member, said pawls being provided with lugs with which said rods are slidably engaged, and springs arranged on said rods and acting to release the holding pawl and engage the reversing pawl on 110 the actuation of said reversing member. 115

3. In a lifting jack, the combination of a frame, a lifting member, a drum operatively connected to said lifting member, a clutch member provided with a rack and with a clutch shoe coacting with said drum, an actuating lever pivoted on said clutch member to coact with said clutch shoe, a spring acting to normally urge the clutch shoe to engaging position, a holding ratchet connected to said drum, a holding pawl coacting with said holding ratchet, a reversing pawl coacting with said rack on said clutch member, a rotatably mounted reversing member provided with a rack and with radi- 120 125 130

ally disposed arms, a reversing member actuating dog, a supporting link for said dog, a spring acting to hold said dog normally in disengaged position, and a control rod 5 connected to said dog whereby a pull will first engage the dog with the reversing member and a continued pull will actuate the same.

4. In a lifting jack, the combination of a frame, a lifting member, a drum operatively connected to said lifting member, a clutch member provided with a rack and with a clutch shoe coacting with said drum, an actuating lever pivoted on said clutch member 10 to coact with said clutch shoe, a spring acting to normally urge the clutch shoe to engaging position, a holding ratchet connected to said drum, a holding pawl coacting with said holding ratchet, a reversing pawl 15 coacting with said rack on said clutch member, and a rotatably mounted reversing member provided with radially disposed arms.

5. In a lifting jack, the combination of a frame, a lifting member, a drum operatively connected to said lifting member, a clutch member provided with a rack and with a clutch shoe coacting with said drum, an actuating lever pivoted on said clutch member to coact with said clutch shoe, a spring 20 acting to normally urge the clutch shoe to engaging position, a holding ratchet connected to said drum, a holding pawl coacting with said holding ratchet, a reversing pawl coacting with said rack on said clutch member, a rotatably mounted reversing member provided with a rack operatively associated with said pawl to release the holding pawl and engage the reversing pawl 25 on the actuation of said reversing member, 30 a reversing member actuating dog, a supporting link for said dog, a spring acting to hold said dog normally in disengaged position, and a control rod connected to said dog whereby a pull will first engage the dog with the reversing member and a continued pull will actuate the same.

6. In a lifting jack, the combination of a frame, a lifting member, a drum operatively connected to said lifting member, a clutch member provided with a rack and with a clutch shoe coacting with said drum, an actuating lever pivoted on said clutch member to coact with said clutch shoe, a spring 50 acting to normally urge the clutch shoe to engaging position, a holding ratchet connected to said drum, a holding pawl coacting with said holding ratchet, a reversing pawl coacting with said rack on said clutch member, and a reversing member provided 55 with a rack operatively associated with said pawl.

7. In a lifting jack, the combination of a frame, a lifting member, a drum operatively connected to said lifting member, a clutch member provided with a rack and with a

clutch shoe coacting with said drum, an actuating lever pivoted on said clutch member to coact with said clutch shoe, a holding ratchet connected to said drum, a holding pawl coacting with said holding ratchet, a 70 reversing pawl coacting with said rack on said clutch member, a rotatably mounted reversing member provided with a rack and operatively connected to said pawls whereby the holding pawl is released and the reversing pawl engaged on the actuation of said reversing member, a reversing member actuating dog, a supporting link for said dog, a spring acting to hold said dog normally in disengaged position, and a control rod 75 connected to said dog whereby a pull will first engage the dog with the reversing member and a continued pull will actuate the same.

8. In a lifting jack, the combination of a frame, a lifting member, a drum operatively connected to said lifting member, a clutch member provided with a rack and with a clutch shoe coacting with said drum, an actuating lever pivoted on said clutch member to coact with said clutch shoe, a holding ratchet connected to said drum, a holding pawl coacting with said holding ratchet, a 80 reversing pawl coacting with said rack on said clutch member, and a reversing member operatively connected to said pawls whereby the holding pawl is released and the reversing pawl engaged on the actuation of said reversing member.

9. In a lifting jack, the combination of a frame, a lifting member pivotally mounted on said frame, a pair of rack bars pivotally connected to said lifting member in spaced relation to its pivot, an elongated pinion coacting with said rack bars, a drum on said pinion, a clutch member provided with a rack and with an annular split clutch shoe coacting with said drum, an actuating lever pivoted on said clutch member to coact with one end of said clutch shoe, a spring interposed between the opposite end of said clutch shoe and said lever and acting to normally urge the clutch shoe to engaging position, a holding ratchet connected to said pinion, a holding pawl mounted on said frame 100 to coact with said holding ratchet, a reversing pawl mounted on said frame to coact with said rack on said clutch member, and a reversing member operatively associated with said pawls.

10. In a lifting jack, the combination of a frame, a lifting member pivotally mounted on said frame, a pair of rack bars pivotally connected to said lifting member in spaced relation to its pivot, an elongated pinion coacting with said rack bars, a drum on said pinion, a clutch member provided with a rack and with an annular split clutch shoe coacting with said drum, an actuating lever pivoted on said clutch member to coact with

said clutch shoe, a holding ratchet connected to said pinion, a holding pawl mounted on said frame to coact with said holding ratchet, a reversing pawl mounted on said frame to coact with said rack on said clutch member, and a reversing member operatively associated with said pawls.

11. In a lifting jack, the combination of a frame, a lifting member pivotally mounted on said frame, a rack bar pivotally connected to said lifting member in spaced relation to its pivot, a pinion coacting with said rack bar, a drum connected to said pinion, a clutch member provided with a rack and with an annular split clutch shoe coacting with said drum, an actuating lever pivoted on said clutch member to coact with one end of said clutch shoe, a spring interposed between the opposite end of said clutch shoe and said lever and acting to normally urge the clutch shoe to engaging position, a holding ratchet connected to said pinion, a holding pawl mounted on said frame to coact with said holding ratchet, a reversing pawl mounted on said frame to coact with said rack on said clutch member, and a reversing member operatively connected to said pawls whereby the holding pawl is released and the reversing pawl engaged on the actuation of said reversing member.

12. In a lifting jack, the combination of a frame, a lifting member pivotally mounted on said frame, a rack bar pivotally connected to said lifting member in spaced relation to its pivot, a pinion coacting with said rack bar, a drum connected to said pinion, a clutch member provided with a rack and with an annular split clutch shoe coacting with said drum, an actuating lever pivoted on said clutch member to coact with said clutch shoe, a holding ratchet connected to said pinion, a holding pawl mounted on said frame to coact with said holding ratchet, a reversing pawl mounted on said frame to coact with said rack on said clutch member, and a reversing member operatively connected to said pawls whereby the holding pawl is released and the reversing pawl engaged on the actuation of said reversing member.

13. In a lifting jack, the combination of a frame, a lifting member, a drum operatively connected to said lifting member, a clutch member provided with a rack and

with a clutch shoe coacting with said drum, an actuating lever pivoted on said clutch member to coact with said clutch shoe, a spring acting to normally urge the clutch shoe to engaging position, a holding ratchet connected to said drum, a holding pawl coacting with said holding ratchet, a reversing pawl coacting with said rack on said clutch member, and a reversing member operatively connected to said pawls to release the holding pawl and engage the reversing pawl on the actuation of said reversing member.

14. In a lifting jack, the combination of a frame, a lifting member, a drum operatively connected to said lifting member, a clutch member provided with a clutch shoe coacting with said drum, an actuating lever pivoted on said clutch member to coact with said clutch shoe, a holding ratchet connected to said drum, a holding pawl coacting with said holding ratchet, a reversing pawl coacting with said clutch member, and a reversing member operatively connected to said pawls to release the holding pawl and engage the reversing pawl on the actuation of said reversing member.

15. In a lifting jack, the combination of a frame, a lifting member, a drum operatively connected to said lifting member, a clutch member coacting with said drum, an actuating lever operatively associated with said clutch member, a holding pawl for said drum, means operatively associated with said clutch, permitting the releasing of the clutch by manipulation of said actuating lever, and means for actuating such releasing means operatively connected to said holding pawl whereby the holding pawl and said releasing means are alternately engaged and disengaged.

16. In a lifting jack, the combination of a frame, a lifting member, a drum operatively connected to said lifting member, a clutch member coacting with said drum, an actuating lever operatively associated with said clutch member, a holding means, clutch releasing means, and means for actuating such releasing means operatively connected to said holding means whereby the holding means and said releasing means are alternately engaged and disengaged.

In witness whereof I have hereunto set my hand.

ARTHUR C. HOPKINS.
